J. H. REIGHARD.

Lantern.

No. 19,207.

Patented Jan. 26, 1858.

J. H. Reighard

UNITED STATES PATENT OFFICE.

JACOB H. REIGHARD, OF BIRMINGHAM, PENNSYLVANIA.

LANTERN.

Specification of Letters Patent No. 19,207, dated January 26, 1858.

To all whom it may concern:

Be it known that I, JACOB H. REIGHARD, of Birmingham, in the county of Allegheny and State of Pennsylvania, have invented a new and useful Improvement in Lanterns; and I do hereby declare the following to be a full, clear, and exact description thereof, reference being had to the annexed drawing, forming part of this specification, which is 10 a perspective view of a lantern constructed with my improvements.

In the drawing like letters of reference designate similar parts of my lantern.

My improvement consists in the arrangement and construction of the top and bottom trimmings of lanterns, so that they may be readily attached to or removed from the glass globe.

As lanterns are usually constructed, the 20 trimmings are fastened to the glass globe with cement, so that in case of the breaking or destruction of either of the trimmings, or of the glass globe, they cannot be easily separated from each other, and cannot be 25 used again. Also, in lanterns, where the lamp is fastened into the bottom trimming with springs, the lamp is liable to come out, if the lantern is swung about, as in the case of making signals by railroad employees.

30 Also, if the lamp is placed upon a heated stove, as is frequently done in cold weather, there is a liability of the solder being melted. Also, when it is desired to remove the lamp from the glass globe, or the bottom trimming, the hand is often burned by grasping the top trimming which is heated by the flame of the lamp. In my improvement, all 35 these objections are obviated, and in a very simple manner, the different parts of my 40 lantern being so contrived, that they are easily put together or detached from each other, either the top or bottom trimmings can be removed from the glass globe and replaced in a very short time, and in case of 45 the glass globe being broken, a new one is very easily replaced, without the assistance of a mechanic skilled in such matters. In 50 removing the lamp or the bottom trimming, there is no danger of burning the hand, as the lantern can be held by the ring, which, as will be hereafter shown is fastened to the top trimming of the lantern.

To enable others skilled in the art, to make and use my improved lantern, I will 55 proceed to describe its construction.

The glass globe *a* of the lantern as shown in the drawing is made of one piece of glass, and is blown in a mold. On the outside of the lower part of the glass globe, is a bead or projection *d* around its neck, against 60 which rests the upper edge of the bottom trimming, when the globe is in its place. This bead *d* does not pass continuously around the neck of the glass, but is intermittent at two points opposite to each other, 65 to allow the passage of two hooks or lugs *f, f* attached to the bottom trimming *e* of the lantern. These lugs rise perpendicularly from the upper edge of the bottom trimming about $\frac{1}{2}$ an inch and on opposite sides of the 70 circumference. They are curved so as to fit closely on the bead *d* in the glass. The neck of the glass globe is put down into the bottom trimming *e* of the lantern, until the bead rests on the upper edge of it, the two 75 lugs *f, f* passing the bead at the two points where it is intermittent. The glass globe *a* being then turned, the lugs *f, f* pass over the bead *d* fitting so closely to it as to prevent the removal of the glass without turning it 80 around, until the lugs *f, f* come to the points where the bead stops. The bottom trimming *e* can then be removed whenever the lamp is to be lighted or trimmed.

The top trimming *g* is attached to the 85 glass globe *a* in precisely the same manner as the lower trimming *e* (hereinbefore described) by the lugs *f', f'* extending downward over a bead *d'* passing around the upper neck of the glass globe *a* correspond- 90 ing to the bead *a* on the lower neck of the globe. In order, however, to prevent the top trimming *g* from turning around, and to keep it firmly in its place, I make a slide *h* which after the glass globe is adjusted for 95 use, is pushed down into one of the spaces intermittent in the bead *d'* and this slide *h* fitting closely into this intermission in the bead *d'* prevents the top trimming from 100 turning around on the glass globe, and removing all possibility of the separation of the two parts, until the slide *h* is raised. The top trimming *g* is thus easily removed from the rest of the lantern, if desired. The ring *n*, as seen in the drawing, not turn- 105 ing on a swivel, as is usual in lantern trimmings, but being firmly fastened to the top trimming *g* enables a person desiring to remove the bottom trimmings, when the lamp is lighted, without taking hold of that part 110

- of the top trimming immediately above the glass globe, which is always very much heated; the ring *n* the top trimming *g*, and the glass globe *a* by means of the slide *h* forming a continuous resistance sufficient to allow the bottom trimming *e* to be turned around on the glass globe, by taking hold of the ring with one hand and of the bottom trimming with the other.
- 10 The bottom trimming *e* containing the lamp *c* has a flange *p* extending below the bottom of the lamp far enough to prevent injuring the lamp by its being placed upon a stove or otherwise exposed to heat which might melt the solder by which the lamp and the other part of the bottom trimming are fastened together. This flange *p* is also a convenient handle by which to turn the

bottom trimming in taking out or putting back the lamp into the glass globe.

20

What I claim as my invention and desire to secure by Letters Patent is—

Attaching the top and bottom trimmings of lanterns to the globe by means of lugs, fitting on a bead around the upper and 25 lower neck of the glass globe so that they may be more readily attached or removed, or a new globe inserted when necessary, in the manner hereinbefore described.

In testimony whereof I have hereunto set 30 my hand this twenty fourth day of August, A. D. 1857.

J. H. REIGHARD.
